UNITED STATES PATENT OFFICE.

MAGLOIS P. DU PRAY, OF TRENTON, NEW JERSEY.

PROCESS OF WEAVING MULTIPLY TUBULAR FABRIC AND APPARATUS THEREFOR.

1,357,967.

Specification of Letters Patent.

Patented Nov. 9, 1920.

Application filed January 14, 1916. Serial No. 72,152.

To all whom it may concern:

Be it known that I, MAGLOIS P. DU PRAY, a citizen of the United States, residing at Trenton, in the county of Mercer and State 5 of New Jersey, have invented certain new and useful Improvements in Processes of Weaving Multiply Tubular Fabric and Apparatus Therefor, of which the following is a specification.

- 10 This invention relates to processes of weaving multi-ply tubular fabric and apparatus therefor; and it comprises a process of weaving a preliminary tubular fabric and substantially simultaneously weaving a secondary 15 or outer tubular fabric in place upon the first tubular fabric, the direction of weaving of the preliminary tubular fabric advantageously being in a direction opposite to the direction of weaving of the secondary 20 or the outer tubular fabric; and it comprises an apparatus having a plurality of sets of shuttles, weaving pins, heddles, warp and weft thread tensioning devices, and operating mechanism for each set of such devices 25 arranged in such manner that one set will operate to weave fabric upon a tube of fabric preliminarily woven by the other set, and advantageously arranged to cause one set of said devices to weave a circular ply of fabric 30 in one direction while the other set weaves a circular ply of fabric in the opposite direction but directly upon the ply woven by said first set of devices; the invention also comprises a duplex circular loom 35 having superimposed shuttles and means for operating the shuttles at one elevation in a direction opposite to the direction of travel of the shuttles of another elevation, together with a set of heddles for each set of shuttles 40 and mechanism for operating each set of heddles in unison with the particular shuttle for which such heddles make the sheds; the invention further comprises a circular loom having superimposed shuttles together with 45 complementary heddles and mechanism for operating the shuttles and heddles, and an elongated weaving pin having weaving surfaces in proximity to the layers of each set of shuttles; and the invention further comprises 50 certain improvements in shuttles for duplex circular looms, in take-off mechanism for pulling the finished multi-ply fabric from the weaving pin after the last ply of fabric has been woven, certain improvements in warp and weft tensioning means, and certain improvements in heddles and 55

heddle-operating mechanism; all as more fully hereinafter set forth and as claimed.

Multi-ply tubular fabric has heretofore been commercially manufactured to some 60 extent by an expensive and difficult process consisting in the separate and independent weaving of two single-ply tubes of fabric and in the drawing of one of said tubes within the other. Machines for drawing 65 one tube into a second must be powerful as there is a tremendous amount of friction between the inner and outer tubes. It has also been proposed to interweave the different plies of circular double ply fabric. 70

It is a desideratum in the art to which the present invention relates to produce a multi-ply tubular device such as gas tubing, fire engine hose, and the like, in an inexpensive and thoroughly efficient manner without the 75 necessity of drawing one tube within another and without resorting to complicated inter ply weaving apparatus. I accomplish this in my process and in my new loom by weaving one ply of fabric directly upon another and advantageously in such manner that interstices or rugosities of the nethermost or inner ply are filled by the threads of the uppermost or outer ply, whereby the two plies are in effect locked together in surface 80 engagement and the non-leakable properties enhanced. 85

In the accompanying drawings I have shown one form of mechanism for weaving the multi-ply tubular fabric according to 90 my process and I herein claim the general construction and arrangement of such machine together with the improved details which adapt it for its purpose, as well as the process which may be performed by 95 other mechanism or by the particular loom here disclosed.

Figure 1 is a vertical sectional elevation of the duplex loom, showing superimposed shuttles. 100

Fig. 2 is a top plan view in section on lines II—II (Fig. 1), showing the take up drive, and warp tension means, with parts broken away showing part of the lower warp tension. 105

Fig. 18 is a perspective view of the heddle frames and their operating mechanism.

Fig. 19 is an enlarged sectional elevation of finished fabric take-up rolls, parts being broken away to show certain details.

Fig. 20 is a sectional plan view of the take-up rolls.

Fig. 21 is a perspective view of one of the take-up roll gripper pin bars.

Fig. 22 is in the drawings, 1 indicates the base of the loom upon which are mounted the framing uprights 2 which support the shuttle guides or race-way annular frames 3, 4, 5 and 6. Tubular column 7 is secured to the base 1 by the bolts 8 passing through flanges 9, and free running heddle-operating drums 10 and 11 are journaled around this tubular column.

The drum 10 is provided with an integral hub extension 12 upon which is fixedly mounted the beveled gear 13, and, correspondingly, the cam drum 11 is provided with a hub extension 14 upon which is fixedly mounted the oppositely disposed beveled gear 15. These beveled gears and thus the drums (10 and 11) are driven in opposite directions by beveled pinion 16 fixed to the main drive shaft 17. This drive shaft has a bearing in one of the vertical uprights 2 and is journaled in a bracket 18 mount-

ed upon the base (1). The main driving shaft (17) operates the heddles for both sets of shuttles through the cam drums (as more fully hereinafter described), and also drives the shuttles through the spur gear 19 which is fixed upon the upper hub extension 20 of drum (10). This spur gear (19) drives a plurality of circumferentially disposed shuttle operating pinions 21 mounted on a plurality of vertical shuttle driving shafts 22. The lower shuttle disposed between the shuttle race-way annular frames (3 and 4) is driven by the horizontally disposed spirally cut spur pinions 23 meshing with the segments of spiral cut external rack or toothed annulus 24 mounted upon the frames and webbing 25 of the shuttles. These segments and pinions are cut spirally to eliminate some of the noise prevalent where straight cut teeth are used. The upper shuttles disposed between shuttle race-way annular frames (5 and 6) are driven by the horizontally disposed spiral cut pinion 26, meshing with internal rack or toothed annulus 26a.

Shuttles.

The construction of the shuttles may be the same, the upper set however being inverted with respect to the lower set. The frame (25) of each shuttle carries ball bearing traction wheels 27 which comprise outer flanged ball race-way 28 provided with an inwardly disposed stem or bolt and threaded portion 29 for clamping to the frame (25) by nut 30. The traction wheel also is provided with an inner flanged ball race-way 31 which is threaded to fit the stem (29) and which acts as a lock-nut. This race-way may be adjustably clamped to take up all lost motion in the free bearing rings or treads 32 and 33 bearing on the tapering shuttle guide tracks 34 and 35. Lost motion can be taken up by releasing nut 30 and turning stem (29) in flange (31) by the hexagon socket 36, thus drawing rings (32) and (33) together. In shuttles as heretofore made there are no successful expedients for taking up lost motion, and since the shuttles must travel at a considerable rate there is always more or less wear. According to my invention I provide the above described wear compensating device with a result that ultimately there is less wear on the tracks and on the wheels because as slight wear occurs the parts may be adjusted and the "knocking" which results in augmenting the wear eliminated. The traction rolls may be provided with felt washers as is shown at 37, 38 and 39, to prevent grease working out and the lint from the threads working in. The bearing rings (32 and 33) may be hardened on their surfaces to prevent excessive wear. These rings (32 and 33) are so disposed on the guide tracks (34 and 35) that

the conical bearing surface rolls over the radial slits 40 in the tracks, which slits are provided to receive the warp threads. The parallel sliding relation of the conical rings 5 to the tracks is such that all chattering, and attending noises, are eliminated.

One of the main advantages of my improved shuttle is that the filling or weft thread may be used from "universally wound" bobbins; and these bobbins may be of the commercial form now to be found upon the market. As the thread comes from the mill it is wound on straight paper tubes and these tubes may be used as the bobbins in my shuttle without any rewinding on other spools, cops or other forms of spindle. The shuttle is provided with an arm 41 fulcrumed at 42 on the bobbin-center bracket 43. To place the bobbin in the shuttle this arm (41) is lifted to the position shown in Fig. 8 (so far as the lower shuttles are concerned). Cam 44, integral with the arm, engages a projecting pin 45 mounted to slide in sleeve 46 of bracket (43). This pin (45) projects from the center cone 47 which is housed in the sleeve (46), coiled spring 48 serving to normally project the cone center. As main arm (41) is lifted, the cone is retracted from engagement by the cam (44) with the pin. The cam is provided on its periphery with a depression 49 which serves to limit the movement of the arm and to yieldingly lock the arm in lifted position. The right hand spindle 50 is also retracted by the movement of arm (41) through depending auxiliary arm 51, knee piece 52 and slide 53 which engages conical cup 54 surrounding the right hand center (50). As the slide (53) is moved toward the right, because of the elevation of arm 41, the conical cup (54) and center or cone (50) are moved toward the right in substantial unison with the opposite movement of cone or center (47). Spring 55 serves to hold the right hand center and conical cup in normal position. This cup (54) engages the periphery of the bobbin and as the latter gradually diminishes in diameter feeds forwardly and, the spring 55 gradually losing its tension, causes the cup to exert a gradually decreasing pressure upon the right hand edge of the bobbin. In its open position the arm (41) has drawn away the two cone centers and also has lifted any warp threads that may be lying across it, such warp threads having been previously released from tension in the manner hereinafter described. The bobbin is merely placed in position by one hand and the arm (41) is brought to a horizontal plane. This releases the centers so that they may enter the opposite ends of the paper tube 56 and the conical cup (54) engages the periphery of the bobbin at one end. As stated, as the bobbin unwinds the

tension is maintained in proportional relation to the diameter of the bobbin and the peripheral unwinding speed. Spring (55) gradually weakens and the knee piece (52) gradually settles back to close proximity to arm extension (51) as is shown in dotted lines in Fig. 7. The upper set of shuttles is identical with the lower set except that it is in inverted position and the arm (41) is lowered to remove the bobbin and replace a new one, in lieu of being raised. In operation they work in synchronism.

The weft thread coming from the bobbin (see Fig. 4) is designated by the reference letter A. As it unwinds from the bobbin it passes over a conical tension spindle 57 (shown in section in Fig. 14). This spindle is held free to revolve on adjustable post 58 mounted in arm 59, fulcrumed on ear 60, integral with the shuttle frame. 61 is a leather washer interposed between arm (59) and spindle (57) against which the spindle rotates. The arm (59) is provided with a spring equalizer connection 62 coupled at 63 on arm (59) and having its other end guided in the socket 64 swiveled at 65 to the frame (25). Spring (62) interposed between the arm (59) and socket 64 imparts a downward movement to the spindle (57) in the case of the shuttles of the lower frame and an upward movement of the spindle 57 in the case of the shuttles of the upper frame when the thread in unwinding travels from one end of the bobbin to the other, thus centralizing the thread and equalizing the lengthening and shortening of the thread due to the differences in length of the thread from different points of the bobbin to the spindle. The weft thread passes over the spindle (57), over the shive-wheel 66, to the conical grooved tension wheels 67 and 68, and such thread may be passed back and forth over these latter two wheels until the proper tension is attained. Tension wheels (67) and (68) are freely mounted on studs 69 and 70, on an arm 71 of the frame (25) and each wheel is pressed against friction washers 72 by spring 73 adjustable by nuts 74. From the tension wheels (67) and (68) the weft or filling thread passes through guide 75 and alternately under and over spring tension fingers 76 and then over wheel 77 through the eye of the layer. The layer may be similar to heretofore known layers but the particular layer I use is improved by the provision of the spring tension fingers (76) and the alining means for the layer now to be described. To assist in alining the layer and shuttle and to equalize the weight of the same, or to balance the shuttle for the purpose of taking some of the strain off the side traction wheels (27), I provide additional traction wheels or rollers 78 supporting the weft

layer. These traction wheels or rollers are spaced equally around the weaving pin 250 and thus the layer arm will always have a bearing on two or more of these wheels. In 5 actual use I provide six of these wheels. The layer will tend to pack the weft thread as it rotates around the weaving pin and is firmly, but yieldably, held against the threads by means of these wheels. Wheels 10 78 are pivoted at 79 and have a shelf 81 projecting from arm 80. Between this shelf and the loom frame there is interposed a coil spring 82 which serves to yieldingly hold the layer in proximity with the weaving 15 pin. This packs the weft thread as well as provides a yielding bearing for the shuttle as a whole. The layer is provided with a compensating arm 83, which is connected at one end 84 to the shuttle frame and at the 20 other end 85 to the layer. This compensating arm is provided with a screw-threaded portion 83^a located in socket 86 and may be adjustably set therein by nut 87 and locked into position by nut 88. The socket 25 86 slides in sleeve 89. Located within the socket and bearing on the shouldered portion 90 is a coiled compression spring 91 which serves to hold the portion 83^a in a forwardly extended position. The spring 30 finds its bearing at the opposite end 92 in a cup 93. This compensating device is advantageous in that it compels the layer to uniformly pack the threads, even though there 35 may be considerable vibration in the shuttle and even though there may ultimately be some wear in the working parts.

There is very little difference between the upper and lower shuttles. The different features of the upper shuttle, disposed between frames 5 and 6, comprise as shown in Figs. 3 and 6, centrally disposed spiral pinions (26), which are mounted on the upper end of the shafts (22) and engage an internal rack (26^a), on the shuttle frame 97. 40 The internal rack (26^a) transmits the rotation in a direction opposite to the direction of the lower shuttle. (See the arrows on Figs. 3 and 4.) The upper shuttle is inverted with relation to the lower. The operator therefore in inserting bobbins in the upper and lower shuttles can operate from the upper side of frame (4) to insert the lower bobbin and from the under side of frame (5) to insert the upper one. The upper shuttle opening arm (41) opens downwardly as indicated in dotted lines in Fig. 6. 55

Heddles and heddle operating mechanism.

In my circular loom substantial, heavy 60 heddle bars 101 may be used (see Figs. 17 and 18). Each is provided with the usual eye 102 and each is secured at one end in groove 103 cut in a rectangular bar 104. Any means for securing these heddle bars in 65 place may be used but I have shown ordi-

nary screws 105 for this purpose. This construction is advantageous in that one heddle bar and frame can be removed if necessary without displacement of any of the others.

There are two separately operated sets of 70 heddles, one for the lower warp threads and one for the upper warp threads. The lower set of heddles project upwardly and bar (104) of each is mounted in a framing consisting of rectangular vertical bars 106 secured together by crossbars 107. These bars are mortised in place, and the lower bars 107 of the outer set of lower heddle frames are connected by links 108 to the levers 109 fulcrumed on studs 110 in brackets 111. 75 Projecting upwardly and integral with the levers (109) are spur gear segments 112, meshing with spur gear segments 113 which, in turn, are integral with levers 114. The levers 114 are fulcrumed at 115 and are connected by links 116 to the lower crossbars (107) of the inner set of lower heddles. Levers 114 are provided with cam arms 118 to which are journaled loosely revoluble rollers 119 in engagement with the grooved cam 120 in drum (10). Rotation of this drum imparts the proper movement to the levers (114) which, in turn, operate the crossbars (107) and the heddles connected thereto. Levers (114) also, through engagement of segmental gears (112) and (113), impart the proper motion and the synchronizing motion to levers (109) which, in turn, through links (108) and crossbars (107), impart a motion in the opposite direction to the other 100 frames of heddles of the lower sets. The cam drums make one revolution in the same direction as and in the same relation to their respective shuttles.

The other cam drum 11 is provided with 105 peripheral groove cam 121 in which travel the loosely journaled rollers 122 on cam arms 123 of levers 124. Levers 124 are pivoted on studs 110 and are provided with the segmental gears 125 meshing with segmental 110 gears 126 on the upper heddle operating levers 127. These levers are fulcrumed at 128 and have connecting links 129 to the lower crossbars 130 of the upper heddle frames 131. Levers 124 carry the pivoted links 132 11 connected to the lower crossbars 133 on the other frames 134 of the upper sets of heddles. These two frames of the upper set of heddles are connected at the top by bars 135. The lower heddle frames (106) slide 120 in the frames (131 and 134) of the upper heddles and are held in alignment by lugs (136) on uprights (2).

Each heddle frame of each heddle set must reciprocate in opposite direction to its 125 companion but in unison with the particular shuttles for which it is making the shed. And since these shuttles are driven directly from the drums and since the heddles are driven directly from the drums, it is a very 130

simple matter to synchronize the whole loom. The advantageous feature of this heddle construction and heddle operating mechanism is that the heddles may be driven in synchronization with their particular shuttles. This is accomplished since the drums 10 and 11 are driven in opposite directions by bevel pinion 16, and the spur gear 19, which drives the shuttle frames, is connected rigidly with the upper of said drums. It is only necessary to calculate for the spur gear 19, pinions 21, 23 and 26 and annular racks 26^a and 24.

15 Warp thread tensioning means.

The warp threads B coming from their respective spools must be tensioned. They pass through guide bushings 141 over rods 142 and under rods 143. Both sets of these rods may be removable but I ordinarily make only the upper set of the rods 142 removable and I use a sufficient number of these to secure the correct tension as the exigencies of the process warrant. These rods are located in grooves in the brackets 145, secured to the bedplate (1). From these rods the warp thread passes over tension or evening rolls 146. As the shed is changed there is, of course, a slackening of the warp thread with a resultant difference in the length of the thread at the angle when the shed is formed and central crossing position. There should be some means provided to maintain the proper tension on the thread and to take up this slack. For this purpose arms 147 are pivoted at 148 on the brackets (145). To the upper portions of these arms are journaled the rolls 146 over which the warp thread B passes. These rolls are free to revolve in bearings 149 on arms 147 and have projecting axles 151 which are adapted to seat in cutaway bearings 152 on links 153. Links 153 are pivoted at 154 to the heddle frames 106 in the case of the lower heddles and frame (134) in the case of the upper heddles and are further provided with sockets 155. The rolls (146) may have a surface of leather, fabric or other friction material and may be placed under regulation by means of the brakes 156 having linings of leather or other friction material 157 and normally pressed against the periphery of the rolls by means of stems 158 riding in sockets 159 and coiled compression springs 160 in the sockets. Winged nuts and screws 161 may be used for adjusting the tension of the springs, washers 162 being placed in the sockets to give a surface against which the lower end of the spring contacts. When it is necessary for the operator or attendant to change the bobbin in the shuttle, the tension of the warp threads should be released and this is done by lifting a handle 163 on links 153 and pushing inwardly on a handle 164 on arm

147 until the projecting axles or hubs 151 seat in the sockets (155) on links (153). During the opening and closing of the shed the links (153) positively maintain the evening rolls (146) the correct distance from the 70 heddles and thus keep constant the warp thread tension. After the length of the links (153) is determined with respect to the tension or evening rolls 146, the tension of the threads is constant because of the connection of the arms 153 with the heddle arms.

The upper warp tension device is substantially the same as the lower except, of course, it is inverted. The upper warp 80 threads C coming up from the opening in the bed (1) from any source are preferably disposed in radial parallel groups in order that the operator may have free access to the shuttles. They may be passed up through 85 guides 166 and from thence pass upwardly in substantially radial alignment with the loom over grooved bars 167, thence over a similar tie bar 168. From this latter bar they pass under and over tensioning devices 90 in brackets 169 similar to the tensioning devices in brackets (145). From these tensioning devices and these brackets the threads pass around the evening rolls and thence to their respective heddle bars. It 95 may not be necessary to place a spring in the sockets of the upper warp tensioning devices as the weight of the evening rolls will be ordinarily sufficient, but I make the upper warp tension roll similar to the lower 100 one except that it is inverted.

Woven fabric take-up.

The take-up for the woven fabric comprises two rolls, 201 and 202, the former 105 being free to revolve in journal boxes 204, while the latter is free to revolve in journal boxes 203. Roll 202 is held against roll (201) by the pressure of springs 205 having pressure adjustment in the rear through set 110 screw 206 bearing on the shouldered washer 207. Rolls (201) and (202) are provided on their peripheries with slots 208, housing gripping pin bars 209. The pins 210 carried by these bars are of sufficient 115 length to penetrate the outer ply of fabric and to engage the inner ply, whereby, as they pull the fabric from the weaving pin, they maintain an even tension on both plies. These pins should be of small diameter in 120 order not to injure the fabric. Since the pins are operated in a radial direction, there might be a tendency to tear the fabric and therefore, in order to overcome this, the bars 209 carrying the pins are normally held 125 below the surface of the rolls by springs 211, placed between the depressions or off-set portions 212 in the bars and bands 213 surrounding the rolls. The off-set portions of the bars formed by depressions 212 serve 130

as guiding means operating in engagement with the shoulders 214 in the roller grooves. Bars (209) are advantageously provided on each side with rollers 215 which engage 5 cam plates 216, integral with the boxes (203) and (204). The cams 217 on each cam plate serve to force the pin bars outwardly from the rollers and to push the pins into the fabric just at the point where 10 the chordal distance is the shortest, thus preventing the crowding of the fabric between the pins, which would happen if the pins were fixed unyieldingly in the rolls. Ordinarily the springs 211 will serve to 15 withdraw the pins from the fabric, but in order that there may be positive means for accomplishing this, I place the guide-plates 218 in position to engage the rolls 215 and force the bars in the slots. Set screws 219 20 serve for adjustment of roll 201; roll (202) is yieldingly held in position through the screw and spring arrangement described.

Advantageously the rolls are independently driven by separate pairs of spur gears 25 220 mounted on upper-counter-shafts 221 and 222 (see Fig. 2) and are driven by shaft 223 through separate worm and worm gear drives 224 and 225. Shaft 223 is driven by a pair of beveled gears 226 and 227, the 30 former of which is attached to shaft 223, while the latter is mounted on the vertical shaft 228. Shaft 228 is driven by a vertical disk drive consisting of a plate 229, normally pressed against a drive wheel 230 by spring 231. Advantageously drive wheel 230 is faced with friction material, such as leather, rawhide or the like. For the purpose of adjusting the speed of the take-up rolls, wheel 230 is keyed to shaft 17 and is 35 provided with a grooved hub 231 which is shrouded by a fork 232 threaded on an adjusting screw 233. The screw finds bearing in bracket 234 attached to the bearing (18).

To start or stop the take-up rolls, a handle 45 235 is fixed on stud 236 mounted in the bracket 237 on upright 2. This stud is provided with an eccentric 238 and rod connection 239 leading to a forked lever 240. This lever is fulcrumed on upright (2) at 241 and 50 embraces grooved collar 242 integral with disk (229). When the handle 235 is pulled away from the upright 2 and downward, it will operate to disengage the disk 229 and the driving pulley 230.

55 A hand wheel shaft 243 is also connected by knuckle joint 244 to shaft 223 for the purpose of manually moving the take-up roll.

Immediately after starting the loom in 60 operation, the take-up rolls are thrown into operating position by moving handle 235, whereupon they revolve at a predetermined speed to pull the double or multi-ply fabric from the weaving pin. The speed of these 65 rolls may be adjusted by screw (233).

The weaving pin 250 constitutes an important feature of my invention. It may be considered as a weaving pin having two weaving surfaces 251 with the connecting portion reduced in diameter. The reduced 70 portion serves to guide the fabric from the lower weaving surface to the upper.

While I have described my invention as particularly advantageous in the manufacture of multi-ply tubular fabric, it is obvious that the machine may be used for weaving simultaneously two independent hose or tubings, the first one woven being of considerably less diameter than the second. 80

What I claim is:

1. A multiplex circular loom comprising a base, a central weaving pin having a plurality of weaving surfaces arranged along its length, a plurality of superimposed shuttle raceways and supports therefor, a set of shuttles arranged for travel in each raceway, means for driving the shuttles, a set of heddles for each set of shuttles, operating mechanism for the heddles, and means for drawing the woven fabric from the weaving pin and from one weaving surface to another. 85

2. A multiplex circular loom comprising a base, a central weaving pin having a plurality of weaving surfaces arranged at intervals along its length, a plurality of superimposed shuttle raceways and supports therefor, a set of shuttles arranged for travel in each raceway, mechanism for driving one set of shuttles in one direction and for driving another set in the reverse direction, a set of heddles for each set of shuttles, operating mechanism for the heddles, and means for drawing the woven fabric from the weaving pin and from one weaving surface to another. 95

3. A multiplex circular loom comprising a base, a plurality of shuttle guides arranged in superimposed relation, a set of 110 shuttles adapted for travel in each guide, mechanism for driving the shuttles, a set of heddles for each set of shuttles, mechanism for operating the heddles of each set in unison with its complementary shuttle, 115 a plurality of members each having a weaving surface against which the warp and weft threads from each set of heddles and each shuttle are packed, and means for drawing the fabric from one of said weaving surfaces. 120

4. A multiplex circular loom comprising in combination, a framework, a plurality of weaving surfaces alined within the framework, and a corresponding plurality 125 of weaving mechanisms operative in relatively different directions over said weaving surfaces.

5. A multiplex circular loom comprising in combination, a framework, a plurality 130

of weaving surfaces alined within the frame, a corresponding plurality of weaving mechanisms operative simultaneously to weave a plurality of plies one upon the other.

6. A multiplex circular loom comprising in combination, a framework, a plurality of weaving surfaces alined within the framework, and a weaving mechanism operative over each weaving surface, said weaving mechanisms being simultaneously operative to successively lay a plurality of plies one upon the other.

7. A multiplex circular loom comprising in combination, a framework, a plurality of weaving surfaces mounted within the framework, and a corresponding plurality of weaving mechanisms operative simultaneously to successively lay a multiplicity of plies one upon the other.

8. A multiplex circular loom comprising in combination, a framework, a plurality of weaving surfaces mounted within the framework, and a corresponding plurality of weaving mechanisms operative simultaneously but in relatively different directions to weave a multiplicity of plies one upon the other.

9. A multiplex circular loom comprising in combination, a framework, a plurality of weaving surfaces alined within the framework, a weaving mechanism operative around each of said weaving surfaces, and means for progressing fabric from one surface to another, said weaving mechanisms laying a multiplicity of plies one upon the other as the fabric is progressed.

10. A multiplex circular loom comprising in combination, a framework, a plurality of weaving surfaces alined within the framework, and a corresponding plurality of weaving mechanisms operative simultaneously but rotative in relatively different directions over said weaving surfaces.

45 11. A multiplex circular loom comprising in combination, a framework, a weaving pin mounted in said framework, a plurality of weaving mechanisms operative at intervals along said weaving pin to lay a multiplicity of plies one upon the other, and means for removing the completed fabric from said weaving pin.

12. A multiplex circular loom comprising in combination, a framework, a weaving pin centrally mounted in said framework, a plurality of weaving mechanisms operative simultaneously to weave a multiplicity of plies on said weaving pin one upon the other in successive relation, and means for withdrawing the complete fabric from the weaving pin.

13. A multiplex circular loom comprising in combination, a framework, a plurality of weaving surfaces alined within the framework, a plurality of weaving mechanisms

superimposed in said framework and surrounding said weaving surfaces, said weaving mechanisms being arranged in reversed order with respect to one another, and means for withdrawing fabric woven by said mechanisms away from said weaving surfaces.

14. A multiplex circular loom comprising in combination, a framework, a plurality of weaving surfaces alined within the framework, a shuttle raceway surrounding each of said weaving surfaces, a set of shuttles in each raceway, each set being inverted with relation to the preceding set, means for operating said shuttles simultaneously for laying a multiplicity of plies, and means for progressively the fabric from one set of shuttles to another.

15. A multiplex circular loom comprising in combination, a framework, a weaving pin having a plurality of weaving surfaces, shuttle mechanisms and corresponding heddle mechanisms, each of said shuttle mechanisms consisting of upper and lower annular trackways, a shuttle frame positioned by and rotative between said trackways, and shuttles incorporated in said frame.

16. A multiplex circular loom comprising in combination, a framework, a weaving pin extending through said framework, a multiplicity of axially alined weaving surfaces spaced on said weaving pin, a shuttle mechanism operative around each of said weaving surfaces, and heddle mechanisms around said frame corresponding to each of said shuttle mechanisms, and means for delivering a woven fabric from one weaving surface to the next to receive an additional ply.

17. A multiplex circular loom comprising in combination, a framework, a weaving pin extending through said framework, a plurality of weaving surfaces spaced on said weaving pin, a shuttle mechanism corresponding to each weaving surface, and operative in relatively opposite directions, heddle mechanisms around said framework corresponding to said shuttle mechanisms, and means for progressing a woven fabric from one weaving surface to the next for the laying of additional plies.

18. A multiplex circular loom comprising in combination, a framework, a weaving pin, shuttle mechanisms and corresponding heddle mechanisms, weaving surfaces at intervals on said weaving pin, said shuttle mechanisms being spaced to correspond to said weaving surfaces, means for driving said shuttle mechanisms simultaneously but for independent operations, and means for progressing a woven fabric from one weaving surface to the other whereby said shuttle mechanisms will lay plies one upon the other.

19. A multiplex circular loom comprising in combination, a framework, a weaving pin extending through said framework, a multi-

5 plicity of weaving surfaces spaced on said pin, means for drawing a fabric from one weaving surface to the next, and a plurality of simultaneously driven weaving mechanisms operative to add to the structure of said fabric at each of said weaving surfaces.

10 20. A multiplex circular loom comprising in combination, a framework, a weaving pin extending through said framework, a plurality of weaving surfaces spaced on said pin, means for drawing a fabric from one surface to the next, and a plurality of simultaneously driven but oppositely operative weaving mechanisms for adding to the structure of the woven fabric at each of said surfaces.

15 21. A multiplex circular loom comprising in combination, a framework, a weaving pin extending through said framework, a plurality of weaving surfaces spaced on said pin, means for drawing a woven fabric from one surface to the other, and shuttles rotative around each of said weaving surfaces to add to the thickness of the structure of the 25 progressed fabric, and a set of heddles for each of said shuttles.

20 22. A multiplex circular loom comprising in combination, a framework, a weaving pin extending through said framework, a plurality of weaving surfaces spaced on said pin, means for drawing a fabric from one weaving surface to another, relatively inverted weaving mechanisms positioned opposite each of said weaving surfaces, and 35 means for simultaneously driving said weaving mechanisms to lay a multiplicity of plies of the fabric as the latter is progressed from one surface to another.

25 23. A multiplex circular loom comprising in combination, a framework, a centralized weaving pin extending through said framework, spaced weaving surfaces on said pin, and mechanisms operative axially around said pin and in connection with said weaving surfaces to weave a multiply fabric.

30 24. A multiplex circular loom comprising in combination, a framework, a centralized weaving pin extending through said framework, spaced weaving surfaces on said pin, mechanisms axially operative around said pin in alternately opposite directions to weave a multiply fabric, and means for progressing the fabric from one operative stage to the next.

35 25. A duplex circular loom comprising a base, a central weaving pin having two weaving surfaces, means for weaving multiply fabric thereon comprising an upper and a lower raceway and supports therefor, a 40 set of shuttles arranged for travel in each raceway, the shuttles of one raceway being inverted with respect to the shuttles of the other raceway, means for driving the shuttles, and means for drawing the woven 45 fabric from the weaving pin.

26. A duplex circular loom comprising a base, two shuttle guides arranged at different elevations with respect to said base, a set of shuttles adapted for travel in each guide, the shuttle of one guide being inverted with respect to the shuttle of the other guide, mechanism for driving the shuttles, a set of heddles for each set of shuttles, mechanism for operating the heddles of each set in unison with its complementary shuttle, two members each having a weaving surface against which the warp and weft threads from each set of heddles and each shuttle are laid and means for drawing the fabric from one of said weaving surfaces.

70 27. The combination with a duplex circular loom having a central weaving member provided with upper and lower weaving surfaces, and upper and lower shuttle raceways, of shuttles for each raceway, the shuttle of one raceway being inverted with respect to the shuttles of the other raceway.

75 28. In a circular loom an annular raceway having a pair of tapered vertical tracks thereon and shuttle mechanism comprising a shuttle frame, upper and lower grooved wheels carried thereby and adapted to ride on said tapered tracks and driving means for revolving the shuttles in said raceway.

80 29. In a circular loom, the combination with the loom framework, of a plurality of superimposed synchronism shuttle mechanisms, each shuttle mechanism consisting of a shuttle raceway, a shuttle-frame operative in said raceway, laying mechanism and means for supporting the laying mechanism against the work.

85 30. In a circular loom, the combination with the loom framework, of a shuttle raceway carried by said framework, shuttles operative in said raceway, a layer for each shuttle, means for supporting the layers against the work, and additional means to hold the layers against vibration.

90 31. In a circular loom, the combination with a loom framework, of a shuttle raceway, shuttles operative in said raceway, a layer associated with each shuttle, and means yieldingly mounted below the layers to support the latter against the work.

95 32. In a circular loom, the combination with the loom framework, of a shuttle-frame, a shuttle raceway carrying said shuttle-frame, shuttles in said shuttle-frame, layers associated with said shuttles, and a plurality of rollers carried by said framework and providing an interior support to assist in holding the layers against the work.

100 33. In a circular loom, the combination with the loom framework, of a shuttle frame, a shuttle raceway carrying said shuttle frame, shuttles in said shuttle frame, layers associated with said shuttles, a plurality of traction rollers carried by said frame-

- work and providing an interior support over which said layers ride, and means normally pressing said rollers upwardly to support the layers against the work.
- 5 34. In a circular loom, the combination with the loom framework, of a shuttle frame, a shuttle raceway carrying said shuttle frame, shuttles in said shuttle frame, layers associated with said shuttles, and a plurality of traction devices carried by said framework and supporting said layers, each of said traction devices consisting of a fulcrumed arm, a traction roller revoluble on said arm, and resilient means cushioning 10 said arm, whereby there is provided an interior support to hold the layers against the work.
35. In a circular loom, the combination with a loom framework, of a shuttle frame, 20 a shuttle raceway carrying said shuttle frame, shuttles in said shuttle frame, layers associated with said shuttles, and a yielding support to hold the layers against the work.
36. In a circular loom, the combination with a loom framework, of a shuttle frame, a shuttle raceway carrying said shuttle frame, shuttles in said shuttle frame, layers associated with said shuttles, and a plurality of yieldingly mounted traction rollers carried by said framework and forming an interior support for holding the layers into contact with the work.
37. In a circular loom, the combination with the loom framework, of a shuttle frame, 35 layers carried by said shuttle frame, a fixed raceway for the shuttle frame, and a yielding support for the layers.
38. In a circular loom, the combination with the loom framework, of a shuttle frame, 40 an annular raceway supporting the outer portion of said frame, layers carried by said shuttle frame, and a plurality of yieldingly mounted rollers providing a cushioned support for pushing the layers into contact with the work.
39. In a circular loom, the combination with a loom framework, of a plurality of superimposed shuttle mechanisms, each consisting of a shuttle raceway, a shuttle frame 45 revoluble in said raceway, and shuttles carried by said frame, and means for driving alternate frames in opposite directions, said means consisting of a driving gear, a plurality of driving shafts common to all of said superimposed mechanisms, and driving connections between said shafts and each of said mechanisms.
40. In a circular loom, the combination with a loom framework, of a plurality of 50 superimposed shuttle mechanisms, each consisting of a shuttle raceway, a shuttle frame revoluble in said raceway, and means for driving alternate frames in opposite directions, said means consisting of a driving gear, a plurality of driving shafts common to all of said mechanisms, and driving connections between said shafts and each of said mechanisms.
41. In a circular loom, the combination with the loom framework, of a plurality of superimposed shuttle mechanisms, each consisting of a shuttle raceway, a shuttle frame 55 revoluble in said raceway, and shuttles carried by said frame, and means for driving alternate frames in opposite directions, said means consisting of a driving gear, annular racks surrounding said shuttle frames, and common driving shafts connecting all of said frames with said driving gear, said driving shafts having spaced pinions meshing with said annular racks.
42. In a circular loom, the combination with the loom framework, of a plurality of superimposed shuttle mechanisms, each consisting of a shuttle raceway, a shuttle frame 60 revoluble in said raceway and shuttles carried by said frame, and means for driving said frames, said means consisting of a driving gear, a plurality of shafts driven by said driving gear, said driving shafts extending into proximity with each of said superimposed shuttle mechanisms, a toothed annulus surrounding each of said shuttle frames, and spaced pinions carried by said shafts, each of said pinions meshing with one of said toothed annuli.
43. In a circular loom, the combination with the loom framework, of a plurality of superimposed shuttle mechanisms, each consisting of a pair of trackways having opposing traction surfaces, a shuttle frame revoluble between said traction surfaces, and shuttles carried by said frame and means for driving said shuttle frames, said means consisting of toothed annuli surrounding each frame between said trackways, driving shafts extending in proximity to all of said shuttle mechanisms, a plurality of pinions carried by said shafts so that each one of said pinions meshes with one of said annuli, and a common driving gear for all of said shafts.
44. In a circular loom, the combination with the loom framework, of a plurality of superimposed shuttle mechanisms operative in said framework, and a heddle mechanism for each shuttle mechanism, each heddle mechanism consisting of sets of oppositely reciprocating frames and heddle bars carried thereby, and the sets of frames for one shuttle mechanism sliding within the sets of frames for the next shuttle mechanism.
45. In a circular loom, the combination with the loom framework, of a plurality of superimposed shuttle mechanisms operative in said framework, and a set of heddle mechanisms for each of said shuttle mechanisms, said heddle mechanisms being disposed

around said framework and including pairs of oppositely reciprocating frames, and the sets of frames for one shuttle mechanism operating within the sets of frames of the adjacent shuttle mechanism.

46. In a circular loom, the combination with the loom framework, of a plurality of spaced weaving surfaces, a plurality of superimposed shuttle mechanisms, each operative around a weaving surface, means for operating said shuttle mechanisms, a common driving means for all of said shuttle operating means, a heddle mechanism for each of said shuttle mechanisms, and means connected to said common driving means for actuating said heddle mechanisms in synchronism with the operation of said shuttle mechanism.

47. In a circular loom, the combination with the loom framework, of a plurality of spaced weaving surfaces, a plurality of shuttle mechanisms each operative around a weaving surface, means extending into proximity with each of said shuttle mechanisms for operating the latter, a common drive for all of said operating means, a heddle mechanism associated with each of said shuttle mechanisms, and actuating devices also driven by said common drive for actuating said heddle mechanisms in synchronism with their respective shuttle mechanism.

48. In a circular loom, the combination with a loom framework, of upper and lower shuttle mechanisms operative in said framework, and heddle mechanisms disposed around said framework and corresponding to said shuttle mechanisms, said heddle mechanisms including pairs of frames mounted to reciprocate in opposite directions, each pair of frames of one shuttle mechanism slidably inclosing a pair of frames of the other shuttle mechanism.

49. In a heddle mechanism for multiplex circular looms, the combination of two sets of heddle frames adapted to form independent sheds, one set of frames being mounted and operative in the other set of frames.

50. In a multiplex circular loom, the combination of two sets of heddle frames, one of said sets of frames being mounted and operative in the other set of frames, a cam-drum for operating each set of frames, means for commonly driving said drums, and means linking said frames to said drums whereby each set of frames is adapted to be operated to form an independent shed.

51. In a multiplex circular loom, the combination of two sets of heddle frames, one of said sets of frames being mounted and operated in the other set of frames, a cam-drum for operating each set of frames, means for commonly driving said drums, and means linking each set of frames to one of said drums, each linking means consisting of a lever reciprocated by one of said drums, a

link connecting said lever to one of the frames of its respective set, a second lever operatively geared to the first mentioned lever, and a link connecting the second lever to the other frame of the set, the operation 70 being such that each set of frames forms an independent shed.

52. In a multiplex circular loom, the combination with a loom framework, of two sets of heddle frames, one of said sets of 75 frames being mounted and operative in the other set of frames, transverse series of heddles carried by each frame, the heddles of one set operating above the heddles of the other set, thread evening means mounted 80 opposite each set of heddles, means extending tangentially with the loom framework for delivering a bank of warp threads to the lower evening means, and means for delivering a bank of radially aligned warp threads 85 to the upper evening means.

53. In a circular loom, the combination with heddle frames and heddles carried thereby of warp thread evening means, said evening means comprising an evening roller, 90 a pivoted arm carrying said evening roller, and a link pivotally connected to the heddle frame at one end and pivotally and detachably connected at the roller to maintain said roller at a constant distance from the heddle 95 during operation and to provide means for releasing the tension of the warp thread by movement of the roller independently of said link.

54. In a circular loom, the combination 100 with a set of heddle frames and heddles carried thereby of an evening roller mounted opposite said frames to reciprocate toward and from the latter, and means pivotally attached to the heddle frames and pivotally 105 and removably attached at the roller to maintain the roller a constant distance from the heddle frames as the frames are reciprocated and to permit inward movement of the roller independent of said means.

55. In a multiplex circular loom, the combination with a set of heddle frames and heddles carried thereby, of an evening roller mounted opposite said frames, means supporting said evening roller for reciprocating movement toward and from said frames, and means for linking said evening roller to said frames in tensioned or slackened position to hold warp threads passed from the roller to said heddles in slack or tensioned state.

56. In a multiplex circular loom, the combination with a set of heddle frames, and heddles carried thereby, of an evening roller positioned opposite said frames, a frame carrying said roller and having a pivotal mounting to permit the roller to be reciprocated toward and from the heddle frames, means carried by said roller carrying frame and braking the roller, links connecting said roller with one of the heddle frames to 130

maintain the former at a constant distance from the heddles, said links having bearings for engaging the roller, and a second set of bearings on said links for engagement with 5 said roller to hold the warp threads passing from the roller to the heddles in slackened condition.

57. A multiplex circular loom comprising two weaving surfaces, means for preliminarily weaving one ply of tubular fabric around one weaving surface, means for advancing said ply to the other weaving surface and means for weaving a second ply upon the first ply at the second weaving surface.

58. A multiplex circular loom comprising two weaving surfaces, means for preliminarily weaving one ply of tubular fabric around one weaving surface, means for advancing said ply to the other weaving surface and means for weaving a second ply upon the first ply, said last mentioned weaving means operating in an opposite direction to that of the said first mentioned weaving 25 means.

59. In a multiplex circular loom, the combination with the loom framework, of two series of heddle mechanisms surrounding said loom framework, each series of heddle 30 mechanisms including two sets of heddle frames, superimposed and oppositely rotative cams drums for operating said sets of frames, one of said drums corresponding to each set, means for commonly driving said 35 drums, a shuttle mechanism corresponding to each series of heddle mechanisms, means directly operative by one of said drums for actuating said shuttle mechanism, and means for operating said shuttle mechanisms 40 in opposite directions in synchronism with their respective heddle mechanisms.

60. A weaving pin for circular looms, comprising an elongated body having spaced elevations along its length, said elevations 45 providing annular weaving surfaces.

61. A weaving pin for circular looms, comprising an elongated body over which a tubular fabric is adapted to be drawn, said body having annular weaving surfaces at 50 spaced intervals along its length and having the portions thereof intermittent said weaving surfaces of reduced thickness.

62. A weaving pin for circular looms, comprising an elongated body having a plurality of weaving surfaces over which a fabric is adapted to be woven, said weaving surfaces consisting of annular elevations formed on said body.

63. A multiplex circular loom comprising 55 a base, a plurality of weaving surfaces against which the warp and weft threads are laid, a plurality of superimposed shuttle raceways and supports therefor, a set of

shuttles arranged for travel in each raceway, means for driving the shuttles, and a set 65 of heddles for each set of shuttles, operating mechanism for the heddles, means for guiding the warp threads which are laid against one of said weaving surfaces from one set of heddles diametrically with respect to the loom whereby access may be had to one set of shuttles, and means for drawing the woven fabric from the weaving surface.

64. In a circular loom, the combination 75 with a loom framework, of superimposed weaving mechanisms carried by said framework and including upper and lower heddle frames, means for feeding banks of warp threads to the loom for the lower heddle 80 frames in tangential relation to the framework and means for feeding warp threads for the upper heddle frames in banks extending radially with relation to the framework.

65. In a circular loom, the combination 85 with a loom framework, of superimposed weaving mechanisms including upper and lower sets of heddle frames, means for feeding warp threads for the upper and lower 90 sets of heddle frames from the bottom of said framework, the warp threads for the lower sets of heddle frames being fed to the loom in banks extending tangentially to the framework, and the warp threads for the 95 upper sets of heddle frames being fed to the loom in banks extending radially with relation to the framework.

66. In a circular loom, the combination 100 with a loom framework, of superimposed weaving mechanisms carried by said framework and including upper and lower heddle frames, means for feeding banks of warp threads to the loom for one set of heddle frames in tangential relation to the framework and means for feeding warp threads for the other heddle frames in banks extending radially with respect to the framework.

67. The process of weaving multi-ply tubular fabric which comprises preliminarily 110 completely weaving one ply around a weaving surface, advancing said ply to another weaving surface and weaving a second ply upon the first said ply.

68. The process of weaving multi-ply tubular fabric which comprises preliminarily completely weaving one ply around a weaving surface, advancing said ply to another weaving surface and weaving a second ply upon the first said ply, the direction of 120 weaving of the preliminary tubular fabric being in a direction opposite the direction of weaving of the second ply.

In testimony whereof, I affix my signature.

MAGLOIS P. DU PRAY,
